UNITED STATES PATENT OFFICE

2,632,473

FRICITION COUPLING FOR VALVE
ACTUATORS

Charles Hollerith, Jackson, Mich., assignor to
Lake State Products, Inc., Jackson, Mich., a
corporation of Michigan

Application December 29, 1945, Serial No. 638,314

2 Claims. (Cl. 137—706)

1

The present invention relates to improvements in dishwashers and the like, being particularly concerned with the drain valve mechanism, and is considered to be an improvement over co-pending application Serial No. 638,273, filed December 29, 1945.

The improvements herein disclosed relate to washing apparatus of the type in which a propeller or impeller or its equivalent is employed to agitate the washing liquid in combination with a drain valve which is open during certain portions of the cycle of operation to drain off the washing or rinsing liquid. While the invention is not so limited in its application, it is especially adapted for use in connection with washing apparatus having an automatic cycle of operation.

It has heretofore been proposed to provide a central opening in a washing vat and extending through this opening a vertical shaft carrying an agitator at one end and having driving connections at its opposite end. The drain valve has been arranged concentrically with the drive shaft, and reference may be had to United States patents, to Davis, No. 1,919,541, and to Huppmann, No. 2,022,637.

According to the present invention, the driven shaft which carries and drives the agitator also carries the drain valve, the agitator and the drain valve being raised and lowered together. In the preferred arrangement, the drive shaft of the agitator merely carries the drain valve with the movement imparted thereto being confined to a creeping action of the drain valve relative to its seat, which is very beneficial to its sealing operation. The arrangement of the construction is such that a minimum number of parts are required in the fabrication of the drain valve and agitator unit.

Thus, one of the objects of the present invention resides in an improved drain valve and agitator assembly for a washing apparatus. Another object of the invention is to provide an improved drain valve agitator assembly for washing machines, in which the drain valve and agitator are carried by a central driven element.

Another object is to provide a drain valve for dishwashers and the like in which the valve has a tendency to creep on its seat to assure sealing over long periods of use.

These and other objects and advantages present in their arrangement, construction, and combination of parts will be more fully appreciated from a consideration of the following description and the appended claims.

2

In the drawings, the figure is a fragmentary view, shown in vertical cross-section, of the drain valve and agitator or impeller assembly, embodying the present invention, the motor housing and motor being shown only in elevation.

As shown, the washing and rinsing vat 10 has a central opening 12 closed by the drain sump 14, the conical portion of which defines a seat 16 for the valve 18. Screws 20 may be employed to support the sump 14 in position. An outlet 22 may connect with a suitable drain pipe (not shown). A suitable non-metallic sealing ring 24 mounted in a groove 26 engages with a seat 16 to close the drain opening.

Supported from the sump 14 through a suitable bracket 28 is an electric motor 30 provided with a driving shaft 32. Between the driving shaft 32 and the driven shaft 34 is a centrifugal coupling unit 36, comprising a collar 38 fixed to the shaft 32 by a pin 40, and a collar 42 adjustably fixed to the shaft 34 by a set screw 44. Weights 46 hinged to the collar 38 through pins 48 and to the collar 42 through hinged links 50 are thrown out into the dotted line position 25 by centrifugal action when the motor 30 is operating. A spring 52 positioned between the collars 38 and 42 is compressed by this action. It will be noted that the shaft 34 has its end 54 supported for axial movement in the upper end of the collar 38.

The shaft 34 extends upwardly through the central support 56 with rotational support being provided by the bushing 58. A seal of suitable construction 60 is provided above the bushing 58. At the upper end 62, the shaft 34 is of reduced diameter to provide a shoulder 64 for the washer 66. Bearing rings 68 supported in grooves 70 in the arced side of the support 56 give axial and rotational support to the valve

40 18 through engagement with a tubular central portion 72 thereof. The impeller 74 is fixed to the shaft 34 by a screw 76. A spring washer 78 is located between the impeller 74 and valve 18, with the washers 80 and 82 taking the wear of 45 relative rotation between the parts. A similar washer is indicated at 84. It is to be understood that the valve 18 is free from the rotational forces of the shaft 34 except for the friction provided by the washer 78.

50 In operation, with the motor 30 off, the spring 52 will lift the shaft 34 into the full-line position shown in the drawings. In this position, the valve 18 is in its open position, being supported on the shoulder 64. When the motor 30 is 55 turned on, the shaft 34 rotates and is lowered

by the centrifugal action of the weights 46. During the short interval required to lower the shaft 34, the slight friction provided by the spring 78 will cause the valve 18 to at least partially rotate before the sealing ring 24 fully engages with the seat 16. When the motor 30 is up to full speed, the valve 18 is firmly closed and at rest upon its seat 16. At the same time, the impeller 74 is rotating with the shaft 34 as a unit. The tendency for the valve 18 to creep upon starting and stopping of the motor will assure uniform wear of the sealing ring 24 and keep the seat 16 wiped clean of foreign matter.

It is to be understood that the control of the drain valve solely through the driven shaft which rotates the impeller 74 is an outstanding feature of the present development.

Having thus described my invention, what I claim as new and desire to be protected by Letters Patent is:

1. In combination with a dishwasher having a vat with a central drain opening, a vertical shaft which is continuously rotated with said opening closed and liquid retained within the vat and extending through said opening into said vat and means for rotating and axially raising and lowering said shaft, a valve mechanism for controlling the draining of liquid from said vat through said opening comprising a fixed valve seat associated with said opening and concentric with said shaft and providing a relatively large annular area contacted by its valve member, a valve member concentric with said shaft, structure for guiding said valve member along the longitudinal axis of said shaft to and from engagement with said seat and for rotational movement about the axis of said shaft relative to said seat, means engaging with said valve member to move the same from its seat upon axial movement of said shaft in a valve opening direction, an operative connection between said shaft and said valve member for urging said valve member toward its seat upon rotation of said shaft upon movement of said shaft in a valve closing direction, said connection including a frictional drive structure between said valve member and said shaft tending to rotate said valve member with said shaft, the frictional area of said frictional drive being relatively small as compared with the area of frictional engagement between said valve member and its seat with the frictional resistance to relative rotation of the larger of said areas being greater than the smaller of said areas whereby said frictional drive is ineffective to rotate said valve relative

to its seat with said valve member in its fully closed position and engaging with said relatively large area.

2. In combination with a dishwasher having a vat with a central drain opening, a vertical shaft which is continuously rotated with said opening closed and liquid retained within the vat and extending through said opening into said vat and means for rotating and axially raising and lowering said shaft, a valve mechanism for controlling the draining of liquid from said vat through said opening comprising a fixed valve seat associated with said opening and concentric with said shaft, a valve member concentric with said shaft, structure for guiding said valve member along the longitudinal axis of said shaft to and from engagement with said seat and for rotational movement about the axis of said shaft relative to said seat, means on said shaft engaging said valve member to move the same from its seat upon axial movement of said shaft in a valve opening direction, said valve member being lowered on said guiding structure into engagement with said seat upon movement of said shaft in a valve closing direction, said means engaging with said valve member to move it from its seat including a frictional drive structure upon said shaft tending to rotate said valve member with said shaft, whereby said valve member assumes different relative rotational positions with respect to said seat upon repeated opening and closing operations.

CHARLES HOLLERITH.
